UNITED STATES PATENT OFFICE.

HENRY S. PRENTISS, OF NEW YORK, N. Y.

CALENDAR-CLOCK.

SPECIFICATION forming part of Letters Patent No. 360,725, dated April 5, 1887.

Application filed August 6, 1886. Serial No. 210,192. (No model.)

To all whom it may concern:

Be it known that I, HENRY S. PRENTISS, a citizen of the United States, residing in New York city, in the county and State of New York, have invented certain new and useful Improvements in Calendar-Clocks, of which the following is a specification.

My invention relates to that class of calendars arranged to be operated by an ordinary clock-movement.

It has for its object the providing of devices whereby the day of the week and of the month and the month of the year may be automatically indicated at all times, and providing for all irregularities in our calendar without manual intervention. It aims also to indicate in the plainest possible manner the things desired—namely, the day of the week and month and the month of the year, and not to have in sight any other letters or figures, so that no error need be made; and it provides, within a case of small dimensions, for showing the above in large and prominent type, so that they may be readily seen throughout a room of large size. The mechanism of both the clock and the calendar is inclosed within a suitable case, which contains, besides the clock-face and preferably below it, three openings or windows, and behind these are the indicating devices, which show successively the several days of the week, names of the months, and the days of the month. The days of the week and the names of the month are arranged about cylinders in a manner well known. The days of the month are arranged upon separate cards, which are held and successively displayed in a novel manner, and which forms a part of my invention.

The time-clock used in connection with my invention may be of any ordinary form. I use, preferably, the ordinary marine movement in illustrating the invention; but any other style of clock-train will do equally well. The office of the clock-train is simply to release the calendar-movement at the proper time. The latter is operated by an independent train and is arranged to require winding only at long intervals.

In the accompanying drawings, which illustrate my invention, Figure 1 is a front view of the clock and calendar. Fig. 2 is a rear

view of the mechanism, showing the two trains or movements and their relation to each other. Figs. 3, 4, 5, 6, and 7 are details of the several parts of the trains and indicating devices.

55

Similar letters refer to similar parts in the several figures.

Referring to the figures, A represents the movement of the time-clock, (see Fig. 2,) the face and hands thereof being shown at the top 60 of Fig. 1.

B is the cylinder carrying the names which indicate the seven days of the week, and b is the shaft carrying the cylinder. C is the similar month-cylinder, and c its shaft.

65

D is the device for holding and displaying the cards indicating the days of the month, d &c. being the separate cards.

E and E' are the movements or rather the two parts of the same movement which operates the calendar, E' being the actuating-spring.

70

To the ordinary hour-hand shaft of the clock A there is geared the wheel a, making one revolution for each two revolutions of that 75 shaft. In other words, it revolves once in twenty-four hours. The arbor of the wheel a carries the cam a', and this is the device which at the proper time—say at midnight—once each day releases the calendar mechanism and 80 changes the date displayed by the latter. Passing across and above the edge of the cam a' is the rod a², having a pin, a³, which rests upon the edge of the cam. The rod a² is pivoted at a', so that the revolution of the cam from its 85 lowest to its highest point will gradually raise the rod a². It is shown in nearly the highest position in Fig. 2. The further revolution of the cam a' will allow the rod a² to drop suddenly until the pin a³ meets the point a⁴ of the 90 cam. At a⁴ the rod a² is jointed to the rod a⁵, which stands or is suspended perpendicularly close to the inside of the case, the end a⁶ being free and turned at right angles, as shown in Fig. 3.

95

The calendar-movements E and E' are normally prevented from running by the device e, Fig. 3, which acts as a brake upon the arbor of the regulating-fan e'. The device e turns upon the point e¹, and the arm e² extends 100 upward, so that its curved end is in the path of the rod a² as it moves downward. When

the rod a^5 falls, which it does by its own weight when released by the movement of the cam a' , the end a^6 strikes the end of e^3 and releases the calendar-train, which is prevented from 5 immediately stopping again by the device presently to be described. It runs until the proper date is shown and it is then stopped. The devices for this will now be considered.

Referring to Figs. 2 and 4 it will be seen 10 that the shaft or arbor f passes through D and communicates motion from the driving-train E to the mechanism E', which regulates the calendar. In these figures, H is the day-wheel, having upon its edge thirty-one teeth; h , and 15 certain blanks, the use of which is hereinafter described. The lever h' engages the teeth of the wheel H successively as the latter is turned in the direction of the arrow shown at the top. The lever h' is pivoted at h^2 , and at h^3 it is jointed 20 to the rod h^4 . This engages the arm h^5 , which is loosely pivoted on the arbor b of the day-of-the-week cylinder B. A disk or ratchet wheel, b' , is employed for revolving the cylinder B. It has seven pins, b^2 b^3 , &c., in it, and 25 the pawl h^6 , operated by the arm h^5 , engages them successively.

Now, when the day-wheel H is turned in the direction indicated by the arrow, which takes place when the train E is released, the lever 30 h' is carried with it until it slips over the edge of the tooth h , which engages it, and then it falls back against the next tooth. As it is carried forward the rod h^4 is pushed upward and with it the pivoted arm h^5 . At the highest 35 point, and just before the lever h' is released from one tooth to the next, the pawl h^6 engages one of the pins b^2 . When the lever h' is released the weight of the rod h^4 and the arm h^5 carries them down quickly, and the day-of-the-week 40 cylinder B is turned thereby in the direction of the arrow one-seventh of a revolution, bringing the next face on the cylinder in view. A locking-arm, h^7 , has its end h^8 of such shape as to fall between the pins b^2 and lock the 45 cylinder in position after it has been actuated as above. Preferably the pawls h' and h^6 are arranged with a limit of movement to carry the cylinder B one-half the desired distance, or one-fourteenth of a revolution, while the 50 locking-arm h^7 , by engaging a pin, b^2 , upon the angular face at its end, and by means of the spring h^9 , carries it the remainder of the distance required. In this way the chance of carrying the cylinder B too far and jumping 55 over one day is avoided. Having performed this operation, it is desired that the calendar-train be stopped when the pawl h' has fallen upon the tooth h of the regulator-wheel or day-wheel H succeeding that at which the 60 train was started, or when it has reached the position to show the proper date.

Looking at Fig. 3, which shows the opposite side of the case from Fig. 4, the bent rod g is secured to the piece g' , which turns loosely 65 upon the arbor c . The upper end of the rod g is acted upon by the pins b^9 at the end of the cylinder B. When the rod a^5 , described, and

its end a^6 strikes the curved end of the rod e^3 , it pushes the latter downward until it clears a^6 , at the right-hand end, Fig. 3, of the latter. 70 This allows the device e to fall back to its original place, to which it tends by the weight e^4 . The rod e^5 is curved about the small wheel e^6 upon the arbor carrying the regulator-fan e' , and, as described, acts as a brake. When 75 the arm e^3 is carried downward by a^6 , the end of the rod e^5 is also carried downward, and at once the lower end of g passes above it by its weight and that of the arm g^2 . This movement of g is limited by the lower end of g^2 , 80 which meets and rests upon the pin g^3 . The train, therefore, is free to run until a pin, b^9 , on the end of the day-of-the-week cylinder B has carried the upper end of the rod g to the left far enough to allow the brake rod e^5 to be 85 raised to engage the edge of the wheel e^6 . This is effected by the rotation of the cylinder B in the manner already described. Each twenty-four hours, therefore, the above operation is 90 repeated by the revolution of the cam a' .

It will now be easily understood how the month-cylinder is revolved. The wheel H revolves once each month. On the same axis with H is fixed the cam J. A pin projecting from the arm J' rests upon the edge of the 95 cam J, the arm J' being pivoted loosely at j . Once each month it is carried to the highest point of the cam, as shown in Fig. 4. A further movement of the cam J will allow the arm J' to descend, which is aided or caused by 100 the spring S. This fall is gradual, the drop of the cam not being perpendicular, but angular. A disk, K, is attached to the arbor c of the month-cylinder C. The arm K' carries the pawl k , which engages successively the 105 pins k^2 k^3 , &c.

K^2 is the retaining click or dog for the month-cylinder C, the operation of which is apparent. At the end of each month, therefore, the cam J, by its revolution, permits the arm J' , which it has previously raised into position to act, to descend and turn the next month into view behind its window in the front of the case. This movement, it will be seen, is effected by the same action of the mechanism 110 E and E' that turns the day-of-the-week cylinder to display the name of the day, and will therefore take place (the movements being set for it) at midnight on the last day of the 115 month.

It now remains to show how the varying number of days in the month are provided for, and how the extra day of February for leap year is indicated.

In Fig. 4, M is the month-wheel, and L is 125 the February wheel. These are both carried about the axis of H by its revolution, M being pivoted at m , and L at l . M is turned once a year—that is, once for every twelve revolutions of H—by means of the planet-movement 130 M', (shown in Figs. 5 and 7,) and which is on the opposite side of the wheel H from M. It will be noticed that at the top of the wheel H in Fig. 4 is a space without teeth. This space

is left by necessity of construction in applying the wheels M and L. On one side of this space a tooth cut in the month-wheel M corresponds with one of the teeth of H. On the 5 other side of the space (the right) one of the teeth in the edge of L corresponds with two of the teeth of H. It will thus be seen that M and L are so placed upon the side of H that they will, as required, cover up the teeth corresponding to the 29th, 30th, and 31st days, 10 which are the only variable ones.

The wheel M is turned by the train M' in a direction opposite to that of H—that is, it turns in the direction indicated by the arrow below it. It turns, as stated, one-twelfth of a revolution each month. If all the months were equal in length and the wheel M had twelve teeth, then each month one of them would coincide with a tooth of H, and no effect would be 15 produced; but some of the months require a day to be cut off, and this is done by bringing one of the curved sections or arcs upon the edge of M to coincide with and therefore cover or cancel one of the teeth in H on the left side of 20 the blank space alluded to. Thus the wheels are now in position for July 31. One month later M has turned to the left one-twelfth of a revolution, and that will bring m' half-way to the tooth on H now engaged by the pawl h'. 25 The space therefore on H without teeth will be the same as now; and as August, the next month, has thirty-one days, the lever h' will be actuated on August 31 by the same tooth, as shown in the drawings. The next month 30 is September, with thirty days. When H comes round the arc of M, between m' and m'', will be opposite the tooth now engaged by the pawl h', and the latter, therefore, without dropping into the notch corresponding to the thirty- 35 first day, will slide over the blank space formed by the combination of H and M until the tooth x allows it to fall, and this corresponds to the first day of the month. The action of M can in this way be understood, December and January having a long space cut from the edge, as 40 July and August have.

The month-wheel M is set for any particular month by means of the wheel J'. (Shown in Fig. 7.) The sun-wheel and J² are united, and by 45 removing the pawl j² the wheel J² may be turned, thus operating the train M', which turns the month-wheel.

The February-wheel L is operated by the month-wheel M. It revolves once in four 50 years—that is, once in four revolutions of M. The wheel L carries a series of pins, l' l'', &c., eight in number. These pins are engaged by the lugs m³ m⁴ when the month-wheel M is in the proper position, which is the case in February. The wheel L will remain in its present position until February, and therefore until then no teeth of H are cut off on the right hand of the blank space. During that month, however, the lug m⁴ will engage the pin l' 55 which is nearest the axis of M and push it forward. Having pushed it partly into the designed place, the end of the dog or arm L'

falls behind the following pin and pushes L into the position where the arc from l³ to l⁴ on its edge will coincide with and so cancel two of the teeth on H. When, therefore, the twenty-eighth tooth of the wheel H has actuated the lever h', the latter will slide over the long blank space formed by the combination of H, M, and L until the tooth x allows it to fall. At that 70 time the arc of the edge of M, which is, in the drawings, just above the arrow-head, will coincide with and cancel the tooth corresponding to the thirty-first day.

After February has passed it is evident that 80 the two teeth cut off from the right-hand space on H must be restored again. This is effected by the second lug, m³, on the side of M, which, in conjunction with the arm l', pushes the wheel L over until the next space cut away 85 from its edge coincides with the two teeth of H in question, and so March and the following months get their full number of days.

In leap year February has twenty-nine days, and therefore but one tooth must be canceled 90 from H in that year. It will be seen that the arc of the circumference of L, which is at the bottom in the drawings, is but one-half as long as the other three, and it will be sufficient to say that when that arc is brought upward, 95 which is the case every fourth year, but one tooth will be cut off from the wheel H, and so one more day, or twenty-nine, will be allotted to this month.

The device for displaying the cards which 100 give the day of the month is shown in Figs. 2, 5, and 6. It is desirable in all calendars that the day of the month be indicated in large figures, and in most if not all calendar-clocks this has been done, if at all, only by the 105 occupation of a large space.

By my invention I am enabled to obtain the use of large figures for every day of the month and display them conspicuously in a very small space. The device consists of eighteen 110 cards, and each card has a number on both sides, with a few exceptions. Each card shows one side and the other alternately as it is brought before the opening in the case. Thus, there being eighteen cards, the card having 115 1 on one side has 19 on the other; that having 2 on one side has 20 on the other, and so on, each card being reversed as it passes around the axis which carries them. The shaft or axis f has two disks, u and u'. These have 120 each eighteen holes, through which pass the wires u³ u⁴, &c. These are turned outward at right angles on each side after passing through the two disks, and each end is again turned inward toward each other, as shown 125 at u⁵ u⁶ in Fig. 5. The cards are suspended from their centers on these wires, which act as bails, as shown. The disks u and u' are constructed with rims u⁷, which prevent the arms of the bails from binding against the 130 faces of the disks. The positions of the cards are shown in Fig. 6 with one presented before the window at 0, against which it rests. It is held in position by its wire resting upon the

stop u^4 . The next following one is prevented from falling by the catch u^5 .

When the axis f is revolved by the releasing of the train, as described, the card o , 5 Fig. 6, is first drawn slightly upward and backward. Then the short right-angled arm which is attached to the wire u^2 , (one such arm being attached to each of the wires u^2 ,) will clear the stop u^4 , and the card will fall 10 to the bottom and take its place compactly by the side of the others, as shown, and the card o' will fall into the position in front of the window. The card o^2 will at the same time take the place now occupied by o' , and 15 so on. An examination of the figure (6) will show how the mutual positions of the cards on the disks and wires cause their reversal as they are carried upward on the right-hand side, or the side away from the window. As the shaft 20 f turns, the cards are carried up, and, turning naturally on their own axes, are reversed when again presented to view. The pin u^6 aids in keeping the cards which hang below the axis in a proper and compact position until they 25 commence to move upward on the back side.

The time-clock is wound by a key daily, weekly, or otherwise, in the usual manner, and the spring giving motion to the train E and E' is made long and strong, so that it need 30 be wound but once in several months or years.

The device for operating and displaying the cards which give the day of the month is adapted for other uses, and I do not limit myself to its use in calendars or calendar-clocks 35 only.

One of the principal advantages in the device consists in the fact that it presents the surface of the cards close to the inside of the case or window, so that the printed number or 40 other information upon the cards is plainly visible, not only in front, but to a considerable distance on all sides.

It will be seen that normally the time clock 45 which releases the calendar mechanism is entirely disconnected from the latter, being brought into contact with it only when it is desired to release and operate it. Aside, therefore, from raising the rod a^2 upon the surface of the cam a' , which work is regular 50 and equable and may easily be adjusted for, the time-clock has nothing to affect its running rate or qualities.

I claim as my invention—

1. The combination, substantially as described, of a clock mechanism having the twenty-four-hour wheel, a cam driven thereby and revolving once in twenty-four hours, a lever gradually thrown back by said cam and suddenly released at the end of each 55 twenty-four hours, an independent train and its driving-power, a device normally restraining the operation of the last-named train, an arm connected with said restraining device extending into the path of said lever and actuated thereby to release the independent train 60 each twenty-four hours, a calendar indicating apparatus operated by said train, and an ar-

resting device for the calendar indicating apparatus controlled by its own train.

2. The combination, substantially as described, with a clock mechanism and a lever periodically actuated thereby, of the motor-train E , the shaft f , driven thereby, the brake e^5 , released from the motor by said lever, the wheel H , operated by the motor-train, the lever h' and the pawl h^6 , operated by said wheel, and the calendar-movement B , operated by said lever and pawl. 75

3. The combination of a clock-train, a calendar-movement, a motor for driving the calendar-movement, the wheel H , driven by the motor, the month-wheel M and the February-wheel L , both pivoted to the wheel H , the lugs m^3 m^4 , for actuating the wheel L , the planet-movement for operating the wheel M , the pins 85 b^9 , the brake e^5 , applied to the motor, the arm g , serving to restrain the brake e^5 until operated by a pin, b^9 , and mechanism controlled by the wheel H for moving the pins b^9 . 85

4. The combination, with a clock-movement, 90 of an independent motor normally held in check, a tripping device for said motor operated by the clock-movement, the shaft f , revolved by the motor, the bails u^2 , the plates or cards d , independently pivoted upon the bails 95 u^2 , the catches i , and the stops u^4 and u^5 , against which said catches strike, substantially as described.

5. An exhibiting device consisting of a motor, a shaft, f , driven by the motor, the bails 100 u^2 , carried by the shaft, exhibiting cards d , supported from said bails and capable of revolving upon their own axes, and means for holding them one at a time in a perpendicular position and at right angles to the bails, and 105 means for causing them to be reversed at each revolution of the shaft f .

6. The combination, substantially as herein-before set forth, of a time-clock, an independent mechanism consisting of a spring or equivalent motor and a train of wheels, a daily and monthly calendar periodically operated thereby, said calendar mechanism being normally mechanically disconnected from said time-clock, a lever periodically actuated by the 110 clock mechanism to form such connection and release said mechanism at stated times, and a controlling device for the calendar mechanism 115 operating to govern its movements independently of the releasing mechanism. 120

7. The combination, substantially as herein-before set forth, of a time-clock, a wheel attached to said clock which revolves once in twenty-four hours, a cam moving with said wheel, a lever operated by said cam, an arm 125 connected therewith, independently-operated calendar mechanism, and a releasing device for the same periodically operated by said arm, the latter forming a temporary mechanical connection between said time-clock and 130 said calendar mechanism.

8. The combination, substantially as herein-before set forth, of a time-clock having a twenty-four-hour wheel, a cylinder for showing the

days of the week, a cylinder for showing the names of the months, a series of separate cards showing the days of the month, and mechanism for operating said cylinders and cards, 5 said mechanism being normally disconnected from said time-clock, but arranged to be released by the latter at stated times.

9. The combination, substantially as herein-before set forth, of a time-clock, a calendar mechanism disconnected from said time-clock, a pressure-brake applied to said mechanism and normally restraining its movement, and a mechanical device controlled by the time-clock forming a temporary mechanical connection between said time-clock and said calendar mechanism, thereby removing said brake and releasing said mechanism at regular times.

10. The combination, substantially as herein-before set forth, with a clock mechanism, of a calendar-movement consisting of a month, day, and date exposing device, a motor for operating the same, a detaining device consisting of a friction-brake applied to the motor, 25 a tripping device controlled by the clock mechanism for setting the motor in operation, an arm for holding said brake away from said motor when the tripping device has been operated, and a device operated by the calendar-movement for releasing the brake from 30 said arm after the predetermined movement on the part of the calendar.

11. The combination, with a clock-movement, of a calendar-movement, an independent motor for actuating said calendar-movement, a device normally restraining the operation of the calendar-movement, a device for forming a temporary connection between said clock-movement and said restraining device, 40 and a controlling device entirely governed by the calendar-movement for preventing the cessation of the operation of the motor until a predetermined action of the calendar-movement has been accomplished.

45 12. The combination, substantially as herein-before set forth, with a time-clock, of a shaft carrying indicating-marks for the days of the week, means for revolving the shaft step by step, a motor independent of said time-clock 50 for driving the shaft, a friction-brake applied to the motor, a pawl or detent for holding said brake away from the motor, and a device moving with said shaft for withdrawing said detent from the path of said brake upon a predetermined movement of the shaft.

55 13. The combination, with a clock-movement, a series of indicators, a toothed wheel, and mechanism controlled thereby for actuating said indicators, of a motor for revolving said toothed wheel, a second wheel pivoted to the toothed wheel, having their peripheries to coincide at certain points, means for imparting a movement to the second wheel upon its own axis and thereby causing it to cover a tooth 65 of the first-named wheel at stated times, and a device for setting the motor in operation, controlled by the clock-movement.

14. The combination, with a motor, a day-cylinder, and a month-cylinder, of a toothed wheel driven by the motor, a lever controlled 70 directly by said toothed wheel for revolving the day-cylinder each time the motor is set in operation, and a cam moving with the toothed wheel for operating the month-cylinder once during each revolution of the said toothed 75 wheel.

15. The combination of a day-cylinder, a month-cylinder, and a date-exhibiting device, a motor for actuating the same, a wheel driven by said motor, having thirty-one teeth, a lever 80 actuated by the successive teeth for revolving the day-cylinder, a second wheel pivoted to the toothed wheel and having portions of its periphery cut away, and means for revolving said wheel and thereby placing portions of the 85 periphery in the plane of one of the teeth of the first-named wheel at different revolutions of the latter, substantially as described.

16. The combination, in a calendar-movement, of a toothed wheel for operating the 90 day-designating device, eccentrically pivoted to said wheel and having thirty-one teeth, a device revolving therewith for periodically canceling certain of said teeth, a pawl and ratchet or equivalent device for actuating the calendar 95 through the instrumentality of said teeth, and a locking device for interrupting the movement of said wheel after said day-designating device has been operated by one of the teeth.

17. The combination, with a motor and 100 means for periodically locking the same, of a shaft revolved by said motor, a series of bails pivoted to said shaft, cards or other exhibiting devices pivoted to such bails, and stops for arresting each card in a predetermined position successively, thereby exposing the same one at a time, and means for causing each card to be reversed during each revolution of the shaft.

18. The combination of a shaft, pairs of 110 arms extending therefrom and movable independently of the shaft, plates centrally pivoted in such arms and revolving upon their own axes, and also about the shaft as a central axis, and detaining devices for intercepting the same once during each revolution of the shaft, substantially as described.

19. A shaft, a series of cards or plates, arms carried by said shaft to which said plates are independently pivoted, and means for revolving 120 said shaft.

20. A central shaft, a series of cards revolving around it, and themselves revolving upon their own axes and having designating-characters upon one or both sides, and stops for holding them one at a time in a vertical position.

21. In a calendar-movement, a device for exhibiting the names of the months, a revolving snail-cam having its shoulder or drop 130 slightly inclined, and a lever applied to the cam for actuating said device gradually when passing along said shoulder.

22. In a calendar-movement, a toothed

wheel, a device eccentrically pivoted to said wheel and revolving therewith for exhibiting the days dependent upon the number of exposed teeth of the wheel, a device for determining the days of February, consisting of a wheel having four projections, three of which are adapted to cover two of the teeth of the first-named wheel, while the remaining projection is adapted to cover only one of said 10 teeth, and means for revolving the second wheel once in four years.

23. The combination, with a toothed wheel or its equivalent, of means for actuating the

same, a retaining dog or click serving to assist in advancing the wheel during a portion of 15 each forward movement, and having a bearing-shoulder extending at right angles to the direction of the movement of the tooth engaged thereby when the wheel is at rest.

In testimony whereof I have hereunto subscribed my name this 4th day of August, A.D. 1886.
